UNITED STATES PATENT OFFICE.

MARY GARNER TILNEY, OF ORANGE, NEW JERSEY.

DRESS-SHIELD.

SPECIFICATION forming part of Letters Patent No. 722,057, dated March 3, 1903.

Application filed June 10, 1902. Serial No. 110,956. (No model.)

To all whom it may concern:

Be it known that I, MARY GARNER TILNEY, a citizen of the United States, and a resident of Orange, in the county of Essex and State of New Jersey, have invented a new and Improved Dress-Shield, of which the following is a full, clear, and exact description.

This invention relates to improvements in dress-arm shields, the object being to provide a simple means for so securing a shield in place that it may be readily removed when desired and obviating sewing.

I will describe a dress-shield embodying my invention and then point out the novel features in the appended claims.

Reference is to be had to the accompanying drawings, forming a part of this specification, in which similar characters of reference indicate corresponding parts in all the figures.

Figure 1 is a perspective view showing a dress-shield embodying my invention and showing the same in place. Fig. 2 is a section on the line $x-x$ of Fig. 1. Fig. 3 is a plan view of a fastening-device member employed, and Fig. 4 shows the shield and the location of the several fastening devices.

Referring to the drawings, 1 indicates the inner section of the shield, and 2 the outer section thereof. The fastening devices are secured to the upper portion of the two shield members at the sides. Each fastening device consists of a pin 3, attached to one member of the shield and having an enlarged head 4. The other member of the fastening device consists of a disk 5, secured to the other section or member of the shield, and this disk has inwardly-extended yielding fingers 6, between the ends of which the enlarged portion 4 of the pin 3 is to be passed. These pins 3 are to be forced through the material of the dress-waist or the like at the seam portion connecting the sleeve

to the body, as indicated in Fig. 1, and the points are covered by guard-plates 5^a, attached to the plates 5.

The member 1 of the shield is provided at 45 one side near the lower portion with a tape 6^a, which extends outward, and from the end of this tape and extended at substantially right angles thereto are two flaps 7 8. On these flaps the fastening devices are secured. 50 These fastening devices are designed to engage with the seam-lap at the inner side of the body portion of the waist, as indicated in Fig. 1. A similar tape 9 is attached to the inner member 2 of the dress-shield and has 55 two flaps 10 11, to which the fastening devices are secured, these fastening devices being designed to engage with the seam-lap at the inner side of the sleeve.

Having thus described my invention, I 60 claim as new and desire to secure by Letters Patent—

1. A dress-shield, comprising inner and outer members, tapes extended outward from said members near the lower portion, flaps 65 extended from said tapes, and fastening devices on said tapes.

2. A dress-shield, comprising inner and outer members, fastening devices attached to the members at the upper portion, tapes extended outward from the members near the lower portion, flaps on said tapes and extended substantially at right angles thereto, and fastening-device members on the tapes. 70

In testimony whereof I have signed my 75 name to this specification in the presence of two subscribing witnesses.

MARY GARNER TILNEY.
